UNITED STATES PATENT OFFICE.

CHARLES P. SCHLEGEL, OF ROCHESTER, NEW YORK.

DESIGN FOR RIBBON.

47,119.

Specification for Design.

Patented Mar. 16, 1915.

Application filed November 17, 1914. Serial No. 872,671. Term of patent 14 years.

To all whom it may concern:

Be it known that I, CHARLES P. SCHLEGEL, a citizen of the United States, residing at Rochester, in the county of Monroe and State of New York, have invented a new, original, and ornamental Design for Ribbons, of which the following is a specification and of which the accompanying drawing is a representation.

The figure is a plan view of a portion of a ribbon, showing my new design.

I claim—

The ornamental design for a ribbon as herein shown.

CHARLES P. SCHLEGEL.

Witnesses:

WALTER B. PAYNE,
RUSSELL B. GRIFFITH.
